UNITED STATES PATENT OFFICE.

JOHN B. BURDETT, OF CHICAGO, ILLINOIS, ASSIGNOR TO DAVIS-BOURNONVILLE COMPANY, OF NEW YORK, N. Y., AND CHICAGO, ILLINOIS, A CORPORATION OF NEW YORK.

ELECTROLYTIC APPARATUS.

1,154,091.

Specification of Letters Patent. Patented Sept. 21, 1915.

Application filed October 29, 1912. Serial No. 723,387.

To all whom it may concern:

Be it known that I, JOHN B. BURDETT, a citizen of the United States, residing at Chicago, county of Cook, State of Illinois, have 5 made a certain new and useful Invention in Electrolytic Apparatus, of which the following is a specification.

This invention relates to electrolytic apparatus and particularly to apparatus of 10 this nature employed for the electrolytic decomposition of water in the production of oxygen and hydrogen for commercial use.

The object of the invention is to provide an electrolytic apparatus of the nature referred to 15 which is simple in construction, safe and efficient in operation.

A further object is to provide an electrolytic apparatus of the nature referred to wherein efficient separation of the oxygen 20 and hydrogen is maintained.

A further object is to provide means for automatically replenishing the supply of electrolytic or fluid to be decomposed.

A further object is to provide means for 25 insuring the safety of operation of electrolytic apparatus of the nature referred to, with the least possible amount of complication.

Other objects of the invention will appear 30 more fully hereinafter.

The invention consists substantially in the construction, location and relative arrangement of parts, all as will be more fully hereinafter set forth, as shown in the accompanying drawings, and finally pointed out in the appended claims.

Referring to the accompanying drawings and to the various views and reference signs appearing thereon:—Figure 1 is a view 40 partly in front elevation and parts broken out and in vertical section showing a construction of electrolytic apparatus embodying the principles of my invention. Fig. 2 is a similar view in end elevation. Fig. 3 is a top plan view of same. Fig. 4 is a view 45 in horizontal section on the line 4, 4, Fig. 1 looking in the direction of the arrows. Fig. 5 is a broken detail view, partly in side elevation and partly in vertical longitudinal 50 section of the lanterns employed in connection with the electrolytic apparatus embodying the principles of my invention.

The same part is designated by the same reference sign wherever it occurs through- 55 out the several views.

In the construction shown as an embodiment of the principles of my invention, the electrolytic cell comprises essentially a tank or vessel 6 and a top or cover 7 therefor and applied thereto or to the open end thereof, 60 preferably in gas tight relation but electrically insulated therefrom. Simple means for accomplishing this is shown wherein the open mouth or end of the vessel 6 is provided with flanges 8 through which and co-operating flanges 9 in the edge of the cover 7 suitable insulated securing bolts 10 operate to clamp securely the cover 7 down upon the rim of the mouth or opening of the vessel 6, preferably, a suitable packing ring 11 70 is interposed between the cover 7 and the encompassing rim of the vessel mouth.

Suitably sustained within the vessel 6, and from the cover 7 is the electrode member 12, preferably metallic and suitably perforated 75 through the walls and bottom thereof as indicated at 13. In practice and in order to afford means for adjusting the position of the member 12 within the vessel 6, I prefer to employ adjustable suspending devices 80 therefor. Thus, in the form shown, one end of the member 12, is suspended from a rod 14 from the cover 7, while the other end of said member 12 is suspended by means of the adjusting bolts 15 by means of which accurate adjustments of the position of the member 12 may be accomplished by means of the adjusting nuts 16 carried upon the ends of the supporting screw bolts 15, which bolts extend through the cover 7, as shown. This 85 is a desirable feature for the reason that it is important to so adjust the electrode member 12 within the vessel 6 that the opposed surfaces of said member and vessel may lie in substantial parallelism with each other 90 throughout. This is particularly true where the vessel 6 is also metallic and the said vessel and member 12 constitute respectively the terminals or electrodes in the circuit of the source of current employed for effecting the electrolytic decomposition of the electrolyte. For, otherwise, one part of the member 12 would be in closer proximity to the surface of vessel 6 than some other part thereof and consequently, the decomposing 100 action, that is, the evolution of gas would be greater at one point than at another in the apparatus, thereby increasing the danger of commingling of the gases.

Interposed between the opposed surfaces 110

of the vessel 6 and electrode member 12 is a curtain or diaphragm 17, preferably of porous material, such, for instance, as asbestos. In the form shown this curtain is in the nature of a bag surrounding the electrode member 12 but maintained in the space between said electrode member and the inner wall surface of the vessel 6. The cover 7 is provided with a single ring shaped depending flange 18, upon the underside surface thereof, which extends down into the vessel 6 and encompasses the upper end of the electrode member 12. This flange 18 affords a convenient support for the porous diaphragm or curtain 17, said curtain at its upper end being telescoped over the flange 18, as shown and secured thereto in any suitable or convenient manner, as, for instance, by means of a securing band 19 or otherwise, 15 as may be desired. In operation the cover flange 18 extends into the vessel 6 to a sufficient extent for the lower edge thereof to be below the normal level of the electrolyte or liquid to be decomposed, as indicated at 20, thereby forming two separated chambers in the upper part of the vessel 6, one indicated at 21 between the flange 18 and the vessel 6 and the other 22 inside of said flange and above the electrode member 12. 25 The porous curtain 17 continues the separation of the electrode 12 from the vessel 6 below said flange 18. Where the vessel 6 and the electrode member 12 constitute respectively the circuit terminals, the electrolyte is decomposed by electrolytic action 30 which takes place with a resultant evolution of gases at the surfaces of said electrodes, oxygen being given off at the circuit of the positive electrode and hydrogen gas being given off at the surface of the negative electrode. These gases are given off in the form 35 of bubbles which form on the surfaces of the electrodes and these bubbles of gas rise through the electrolyte and collect respectively in the chambers 21, 22, being prevented from intermingling while passing through the electrolyte by the porous diaphragm or curtain 17. 40 Communicating respectively with the chambers 21, 22 are the pipe connections 23, 24 which deliver into the lanterns 25, 26 which in the ordinary manner indicate the operation of the apparatus, and from which service delivery pipes 27, 28 deliver. In the 45 arrangements shown the pipe connections 23, 24 deliver through the bottoms of the lanterns 25 and into a pipe connection 29, see Fig. 5, which extends upwardly into a pipe connection 30, carried by the top or 50 cover 31 of the lantern and depending downwardly therefrom into the lantern with the lower open end thereof immersed below the level of the fluid in the lantern, as indicated at 32. The pipe 29 extends into the pipe 30 through the open end thereof and the upper 55 end of said pipe connection 29 is perforated as indicated at 33. The fluid contained in the lanterns 25 may be water or other suitable liquid or substance capable of absorbing any alkaline spray carried by the gas delivered through the delivery pipes 23, 24, respectively. A five per cent. solution of tartaric acid might well answer this purpose. The upper ends of the depending pipes 30 being closed, it will be understood that the 60 gas delivered into the pipe 30, through the perforations 33 of pipe 29 from the gas collecting chambers, respectively, within the vessel 6, will be forced downwardly through the liquid contained in the lanterns, when the pressure of such gas as collected becomes sufficiently great, the gas passing through the lower open end pipe 30, and then bubbling up through the liquid contained in the lantern and collecting in the 65 upper portion of the lantern and passing therefrom through delivery pipe 27, 28 to a gasometer storage tank or other service connection. By making the lantern bodies 25, 26 of transparent material, such, for instance, as glass, the condition of the cell while in operation as indicated by the bubbling of the gas through the liquid contained in the lanterns will at once be revealed. In order to equalize any differences 70 of pressure of the two evolved gases, namely, oxygen and hydrogen, in the instance above described, I propose to connect the bottoms of the two lanterns 25, 26 by a pipe connection 34, so that any abnormal difference 75 in pressures of the oxygen and hydrogen within one or the other of the lanterns will cause a corresponding lowering of the level of the liquid in the lantern in which the abnormally increased pressure occurs and a corresponding rise in level of the liquid in the other lantern, the difference in the liquid levels being thus utilized to equalize the 80 pressures of the two gases. It is important, however, to prevent the possibility of an admixture of the two gases through the communication between the lanterns, in case an 85 undue increase of pressure in the one or the other of the lanterns should take place sufficient to uncover the point of communication of the pipe connection 34 with such lantern. To prevent this I propose to employ an automatic valve in the pipe connection 34 and preferably at each end thereof where it communicates with the lanterns. In the 90 particular form shown as exemplifying this feature of my invention, I provide pipe connection 34 at each end thereof where it communicates with the lanterns with a valve seat 35 with which co-operates a ball valve 95 36 carried by a float 37, the buoyancy of which normally operates to maintain the valve 36 raised from its seat 35. When, however, the liquid level within the lantern falls to a sufficient degree for the buoyancy 100

of the float 37 to be overcome, the ball valve 36 becomes seated thereby closing the communication between the lanterns and preventing the possibility of the passage of gas 5 collected in said lanterns through the connection 34 to the other lanterns.

It is important to maintain an automatic delivery of electrolyte to the vessel 6, and to control such supply automatically by variations in the level of the liquid contained in the vessel. This is important for the reason that by maintaining a substantially constant level of the electrolyte in the vessel 6, the apparatus is rendered more safe and the 10 danger of the generated gases becoming mixed with each other and forming an explosive mixture is reduced. I have shown a simple arrangement for accomplishing this result wherein a supply connection 38 communicates with the interior of the vessel 6 through the side wall thereof and preferably near the top of the vessel. The outer end of the supply pipe connection 38 is upturned and enlarged as indicated at 39 to 15 form a funnel for the introduction of the electrolyte of the interior of the vessel 6, the mouth of the upturned end portion 39 being flanged to form a seat 40 to receive the shouldered neck portion of a bottle or carboy 41 adapted to be supported therein in inverted position, the neck portion 42 of the bottle depending into the upturned end 39 of the supply connection to a point somewhat below the normal level 20 of the electrolyte to be maintained within the vessel 6. The delivery end 43 of supply connection 38 should also be below the normal level of the electrolyte within the vessel 6. With this construction and arrangement it will be 20 seen that by unstoppering the bottle 41 and placing it in inverted position upon the upturned end 39, with its neck 42 extending into the supply connection to a point below the normal level of the electrolyte within the vessel 6, the bottle will be sealed by the electrolyte against supply of the contents of the bottle into vessel 6 as long as the level of the electrolyte is not maintained at a sufficient height to close the mouth of the bottle 25 neck. Should, however, through inattention or otherwise, the level of the electrolyte within vessel 6 fall sufficiently to uncover the mouth of the bottle, the seal thereof will be broken and the contents of the bottle will 30 flow through the supply connection 38 into the vessel 6 to return or restore and to maintain the proper level of the electrolyte within the vessel.

Another safety feature of my invention 35 designed to prevent an undue interruption of the action of the cell through an undue building up of pressure of the gases within the vessel 6 is also provided and so arranged that when the level of the electrolyte becomes lowered to an undesirable extent from

any cause, the collected gases will escape harmlessly to the atmosphere. Of course the supply connection 38 will perform this function where the delivery end 43 thereof is located near the top of vessel 6. In this case, if the level of the electrolyte is lowered sufficiently to uncover the delivery mouth 43, the gas collected in chamber 21 will escape therethrough and through the connection 38 to the outer air without commingling with the gas contained in chamber 22. Similarly and for a similar safety purpose I provide an escape pipe 44 and arrange the same to extend through the cover 7, the inner end of said pipe extending downwardly 45 into the vessel 6 and preferably into the interior of the electrode member 12, said pipe connection being perforated as indicated at 45, at or adjacent its lower end, said perforated end depending to a desirable depth 50 into the electrolyte which normally seals said escape pipe 44 against escape of gas therethrough. Should, however, the level of the electrolyte fall to a point below the perforations 45, from any cause, then the 55 gas collected in chamber 22 will find ready escape through the escape pipe 44 to the outer air without mixing with the gas contained in chamber 21. In order to still further insure a separation of the evolved 60 gases and to maintain said gases separated without danger of becoming mixed or commingled within the cell, and particularly those gases evolved from the bottom wall 46 of the vessel 6, I propose to arrange a baffle member 47 in the bottom of the vessel 6, constructed of suitable nonconducting material and preferably dish shaped with open peripheral supports or flanges 48, (see Fig. 2). With this arrangement any gas evolved 65 from the surface of the bottom wall 46 instead of passing directly upwardly, therefrom and toward and against the bottoms of the curtain or diaphragm 17 and electrode member 12, said gases are deflected radially 70 and toward the vertical side walls of vessel 6, thereby insuring separation thereof from the gas evolved from the surface of electrode member 12.

It will be observed that the upper end of the diaphragm 17 extends above the upper edge of the inner electrode member 12 and that the flange 18 of the cover depends into the vessel 6 to a point below the upper edge of the inner electrode. This arrangement increases the safety of the apparatus and aids in preventing intermingling of the gases.

Having now set forth the object and nature of my invention and a construction embodying the principles thereof, what I claim as new and useful and of my own invention, and desire to secure by Letters Patent is:—

1. In an electrolytic apparatus, electrodes arranged one inside the other, a porous diaphragm interposed between said electrodes,

a supply pipe connection extending through the wall of the outer electrode and means extending into said supply pipe to a point below and controlled by the normal level 5 of the electrolyte within said electrode for regulating the supply of electrolyte through said supply connection.

2. In an electrolytic apparatus, an inner and an outer electrode, a porous diaphragm 10 interposed therebetween, a supply connection through the side wall of the outer electrode, a supply source associated with said connection and having a delivery end extending into said connection and to a point 15 below to be sealed by the normal level of electrolyte within the electrode.

3. In an electrolytic apparatus, an inner and an outer electrode, a porous diaphragm interposed therebetween, and a supply connection 20 extending through the side wall of the outer electrode, and a supply pipe extending into said connection and having its delivery mouth below the normal level of electrolyte contained in said electrode.

25 4. In an electrolytic apparatus, electrodes arranged one inside the other, a porous diaphragm interposed therebetween, a cover for the outer electrode having a depending flange said porous diaphragm being attached to and supported by said depending flange, said flange depending into the outer electrode and forming separated chambers in the upper end of said electrode, and a safety outlet pipe extending through the 30 said cover and having its inner end immersed in the electrolyte when standing at normal level.

5. In an electrolytic apparatus, electrodes arranged one inside the other, a cover for 40 the outer electrode, said cover having a depending flange extending into said electrode to a point intermediate the electrodes to form separated chambers in the upper end of said outer electrode, a porous diaphragm 45 interposed between the electrodes, said diaphragm being attached to and supported by said flange, said diaphragm extending above the upper edge of the inner electrode.

6. In an electrolytic apparatus, electrodes 50 arranged the one inside the other, a cover for the outer electrode, said cover having a depending flange extending into the outer electrode and between it and the inner electrode, and forming separated chambers in 55 the upper part of the outer electrode, a porous diaphragm interposed between the electrodes, said diaphragm being attached to

and carried by said flange and a safety exhaust pipe extending through the cover and having its inner end depending beneath the 60 normal level of the electrolyte contained within the outer electrode, said depending immersed end of the exhaust pipe being perforated.

7. In an electrolytic apparatus, electrodes 65 arranged the one inside the other, a porous diaphragm interposed between them, means to provide separated chambers, said chambers being respectively associated with said electrodes, a lantern communicating with 70 each chamber, said lanterns being in communication with each other and means for automatically controlling said communication.

8. In an electrolytic apparatus, electrodes arranged the one inside the other, a porous 75 diaphragm interposed therebetween, means to form separated chambers, said chambers being respectively associated with said electrodes, a lantern communicating with each chamber, a pipe communicating between 80 said chambers, and an automatic valve arranged in said pipe.

9. In an electrolytic apparatus, electrodes arranged the one inside the other, a porous diaphragm interposed therebetween, means 85 to form separated chambers, said chambers respectively associated with said electrodes, a lantern communicating with each chamber, a pipe connecting said lanterns, a float arranged in said pipe and a valve carried 90 by said float and controlling the communication from each lantern to said pipe.

10. In an electrolytic apparatus, electrodes arranged the one inside the other, a porous diaphragm interposed between said elec- 95 trodes, means to form separated chambers, said chambers respectively associated with said electrodes, a lantern for each of said chambers, a pipe delivering from each chamber through the bottom of its associated lantern, a cover for each lantern, a pipe carried 100 by each cover and depending into its associated lantern, the depending end of said pipe being open, the pipe connection from the chamber extending into said open end, 105 and a delivery pipe from each lantern.

In testimony whereof I have hereunto set my hand in the presence of the subscribing witnesses, on this 11th day of October A. D., 1912.

JOHN B. BURDETT.
